DESIGN FOR A TABLECLOTH OR SIMILAR ARTICLE

Jacob F. Durré, New York, N. Y.

Application February 15, 1938, Serial No. 75,131

Term of patent 3½ years

To all whom it may concern:

Be it known that I, Jacob F. Durré, a citizen of the United States of America, residing in city of New York, county of New York, and State of New York, have invented a new, original, and ornamental Design for a Tablecloth or Similar Article, of which the following is a specification, reference being had to the accompanying drawing, forming part thereof.

The drawing shows a portion of a tablecloth showing my design, the dot and dash lines indicating one quarter section thereof, the other three sections being identical therewith, arranged in proper relation to complete the cloth.

I claim:

The ornamental design for a tablecloth or similar article substantially as shown and described.

JACOB F. DURRÉ.
